UNITED STATES PATENT OFFICE.

ARTHUR W. WADSWORTH, OF FORT THOMAS, KENTUCKY.

WATCHCASE CRYSTAL.

Application filed July 14, 1919. Serial No. 310,525.

To all whom it may concern:

Be it known that I, ARTHUR W. WADSWORTH, a citizen of the United States, and a resident of Fort Thomas, in the county of 5 Campbell and State of Kentucky, have invented certain new and useful Improvements in Watchcase Crystals, of which the following is a specification.

10 My invention relates to watch crystals or glasses of angular shape, and its object is to provide such crystals in a condition whereby they may be readily fitted to the watch cases without grinding, and with a minimum of chance of breakage.

15 My invention consists in the new and improved article of manufacture and in the process or method of making such article as will hereinafter be more fully described and claimed.

20 In the drawing:

Fig. 1 is a front view of a watch case fitted with a crystal or glass embodying my invention;

Fig. 2 is a front view of the crystal;

25 Fig. 3 is a rear or inside view of the same;

Fig. 4 is an enlarged cross-section of the crystal and bezel fitted together;

30 Fig. 5 is a front view, and Fig. 6 is a partial cross-section very much enlarged, showing, by dotted and solid lines, the first stages of the process of manufacture of my improved crystal;

35 Figs. 7 and 8 are front views, and Fig. 9 is a cross-section very much enlarged showing, by dotted and solid lines, succeeding stages of said process; and

40 Figs. 10 and 11 are cross sections corresponding to Figs. 6 and 9 showing the completion of the process.

The watches of odd shape are very much in vogue, and it is usually desired that not only the case itself be of the odd shape, but that the dial and the crystal be of an odd 45 shape also; it usually being desired that these should conform to the shape of the case. These odd shapes generally involve angles; and when the crystal or glass is made of such angular shape, it is especially difficult to fit it to the bezel so that it will readily snap therein without breaking the crystal at any point. The difficulty is especially aggravated because the corners which such angular crystals have, are extremely liable 50 to breakage when the attempt is made to

force the crystal into the bezel as crystals are usually placed in bezels.

Under conditions heretofore existing, one of these watches with an odd shaped crystal involved a very disproportionate expense for renewing the crystal. Even though the jeweler to whom the watch was taken for this renewal was supplied with a crystal purporting to fit such a watch, he would nearly always find it necessary to carefully grind this crystal to fit the bezel of the watch. This is because, from the nature of odd-shaped glass articles, while the approximate shape may be reproduced, it is practically impossible to produce such glass articles of such exactly uniform shape as will be required to have these odd-shaped crystals perfectly interchangeable among the watch-cases of corresponding shape.

This grinding of these crystals involves a considerable amount of the time of a highly skilled and highly paid workman. Thus, this renewal of this kind of crystal inflicts upon the user of the watch a considerable hardship in the way of deprivation of use of the watch as well as of expense. This latter amounted often to ten or twelve times as much as the expense of renewing an ordinary watch crystal. It was due not merely to the labor of grinding and fitting; but often to the breakage of several such ground crystals in the attempt to fit them in the bezel, before the watch repairer finally succeeded in fitting a crystal to the bezel. Moreover, even when the crystal has thus been made to enter and stay in the bezel after all of this work, it has frequently happened that the crystal did not accurately fit the bezel at every point; so that slight openings were left between the crystal and the bezel for the entrance of dust, moisture and other foreign substances, entirely contrary to the purpose of any well-constructed watch case.

I overcome these disadvantages by providing any such odd shaped or angular crystal with a frame into which the crystal or glass is firmly and permanently secured by the manufacturer, and which frame is formed around its outer edge with suitable means for holding the entire construction in the watch case.

As exemplified herein, the watch case 1 is of quadrangular shape; each one of its sides 2 conforming to an arc struck from a center over near the opposite side of the

case. These arc-shaped sides thus meet in corners or angles 3. Such a case as this is meant when a case of odd or angular shape is mentioned; although it will be understood that many variations from the given example are possible as to number and shape of sides of the case with corresponding variation in the number and sharpness of the corners or angles of the case.

10 The glass 4 of this case is of outline corresponding to that of the case just described; having the four arc-shaped sides 5 meeting in the corners 6. It will also be understood that this crystal 4 is dished as indicated in 15 the cross section in Figs. 4, 10 and 11. These corners 6 of the crystal are, in the present example, rather obtuse; but it will be understood that any corner or projection, however moderate, on a piece of glass, involves 20 very much difficulty in re-producing uniformly and is extremely liable to breakage.

The frame 7, which is preferably continuous has arc-shaped sides 8 meeting in corners 9, and adapted to closely surround 25 the correspondingly shaped edges of the glass 4. These sides 8 of this frame 7 comprise inwardly extended flanges 10 and 11, respectively, adjacent to the rear side and the front side of the frame, and which flank 30 the adjacent edge parts of the glass 4 rearwardly and forwardly. The rear surface 12 of all these frame sides 8 is in a single plane.

The frame 7 fits in the front of the bezel 35 13 where the bezel usually receives the glass directly and where it has very slightly under-cut sides 14 which incline inwardly all around for the crystal edges to snap thereunder. It is in attempting to snap such an 40 odd-shaped crystal under such a part 14 in direct contact therewith that the crystals are broken, and it is the direct fitting of the glass edges to such a part that requires the extreme care in grinding and fitting as 45 before alluded to.

The frame 7 thus embracing the glass 4, has, on its outer edge or periphery, a slight rearwardly facing shoulder 15 to the rear of which is a very slightly rearwardly outwardly inclined part 16. These parts 15 and 16 are so proportioned and located that the part 16 will readily snap inside the under-cut part 14 of the bezel 13, and that the shoulder 15 will come tightly against the 50 outer face of the bezel 13 around the part 14. The bezel 13 used with this new crystal is simple; merely having the opening cut through with its sides 14 slightly undercut. The frame 7 may be of metal or other 55 suitable material.

These co-acting parts may be very readily formed in metal and may be very uniformly re-produced so that any frame 7 will fit anyone of the bezels 13 for which the frames 60 were designed. The glass 4 does not re-

quire to be ground or accurately fitted to this frame because it is permanently mounted therein by burnishing the front flange 11 over the edge part of the glass. This mode of fastening does not require very accurate fitting of the glass to the frame, and any small variation in the glass is covered by these flanking flanges 10 and 11. This mode of fastening also obviates the excessive breakage involved in snapping the crystals 75 directly into the bezels; the breakage in burnishing the frame flange 11 over the crystal edges being almost negligible. Moreover, any occasional breakage in this process is not of a crystal that has involved 80 much labor in grinding as is often the case in grinding and fitting such crystals directly to the bezels.

All of these advantages are permitted by providing the crystal with a permanent 85 frame which, in turn, fits the watch case. It will be understood that this frame is discarded with a broken crystal or glass; no attempt being made by the local jeweler or watch maker to fit a new glass into the old 90 frame. To do this would involve an opening of the burnished flange 11 to be re-burnished onto the new glass; and this would be impracticable because the frame is made very light, and would be so distorted by this 95 opening process that it would not thereafter fit the bezel. Of course, if these frames are 100 of precious metal, they are saved merely as metal and proper allowance made to the customer. But each crystal or glass has its own frame which it receives at the factory and into which it is not attempted to fit any succeeding crystal. In view of these circumstances, it is highly desirable that this frame should be as light as is consistent with preserving its shape so that it will fit the watch bezel and at the same time duly protect the glass during such fitting; and also that the labor of forming this frame with its various 105 necessary parts be reduced to a minimum. 110

I prefer to manufacture this frame with its enclosed glass according to an improved method of which the several stages are clearly shown in Figs. 5 to 11, inclusive, of the drawing; Fig. 11 showing the improved 115 crystal in its completed stage corresponding to what is shown in Fig. 4 but being on a considerably larger scale, and, therefore, showing this more clearly.

It will be understood that the glasses 4 are 120 furnished by the glass manufacturer in the usual manner and of the particular shape to suit the watch case design for which they are intended.

My improved method is chiefly concerned 125 with the metal frame 7 and the glass 4 itself becomes a factor therein only so far as concerns its final mounting in the frame.

According to this method a flat piece 17 of thin sheet metal (see dotted lines, Fig. 6) 130

is cut so that its outline corresponds to that of the watch crystal which the frame is to receive; and this sheet 17 has its edge parts 18 turned up all around so as to form an extremely shallow cup as seen in Fig. 5 and as shown by the solid lines in Fig. 6.

Then this cup has its upturned sides 18 pressed into the shape shown in Fig. 7 and indicated by the solid lines in Fig. 9 wherein 10 it now has the shoulder 15 and the inclined part 16 on its periphery, and has its flat back 12 completed and has the front part of its cup-side 18 drawn to a forwardly presented thin edge 19 with the outer side inclined 15 rearwardly and downwardly to the shoulder 15 and with its extreme outer part 20 of approximately the shape it is to have when the crystal is finished, and with the inner side substantially straight down to the bottom of 20 the cup.

After this, all of the bottom 21 of the cup, except a narrow stretch all around next to the cup-side, is cut out by a suitable die; whereupon the article is as seen in Fig. 8, or 25 as shown by the solid lines in Fig. 9. This narrow stretch, thus left, constitutes the rear flange 10 of the frame.

By completing all these pressing and forming operations before removing the central 30 part of the cup, the sides are sustained by said central part so that there is no such distortion as there would be in an attempt to perform all of this work on the thin piece of material of which the unfinished article 35 would otherwise consist at this stage.

When the article has been brought to this stage, the glass 4 is readily slipped into it as shown in Fig. 10; it being understood that the frame is made in such proportion to the 40 glass that there will be no hindrance from any slight irregularities or variations in the glass 4 as furnished. Then the thin edge part 19 is pressed or burnished inwardly over the adjacent edge parts of the glass 4 and down closely thereagainst all around; 45 completing the crystal as shown in Fig. 11 ready for snapping into any corresponding watch bezel 13 as shown in Fig. 4. It will be understood that the edge 19 in the actual 50 size is very thin and slight and very readily pressed over the glass without undue pressure on the glass; and yet when so pressed over all around, holds the glass therein permanently, effecting a very tight closure between the glass and its frame. The frame, 55 in turn, being adapted to fit very accurately where it is snapped into the bezel 13, a proper closure of the watch front by such an odd or angular shaped crystal is insured.

60 These crystals, when completed, are placed in new watch cases by the manufacturer, or are supplied in any desired quantity to various jewelers and watch repairers to be kept in readiness by them for renewal of correspondingly shaped crystals in the watches

of their customers. With these provisions thus permitted by my invention, the user of such an odd shaped or angular watch is subjected to no more inconvenience in having its crystal renewed, than would be experienced 70 with any crystal; that is, the user is enabled to have the new crystal applied to the watch at once. And the saving in expense is especially notable; not being necessarily much more than the expense of renewing a crystal 75 of ordinary shape.

While I have shown and described my improved article and method rather specifically in elucidating the construction and use of my invention, as is required, I do not 80 wish to be understood as being limited to such precise showing and description, but having thus fully described my invention, what I claim as new and desire to secure by Letters Patent is:

1. As a new and improved article of manufacture, a watch-case crystal comprising a fragile part having an abrupt change in the direction of its periphery, and a continuous frame around said periphery, having means 90 securely attaching said frame to said periphery, and having its outer edge formed all around to snap into an appropriate part of a watch case.

2. The method of making a combined 95 watch-case crystal and rim, said crystal having an abrupt change in the direction of its periphery, which consists in forming a shallow sheet-metal cup with its walls following the required contour of the crystal, suitably 100 shaping said walls all around to retentively engage a contained fragile part, then cutting out the bottom of the cup excepting narrow stretches around adjacent to said walls to form said rim, and then inserting said fragile part of appropriate contour in said rim and suitably engaging the walls of said rim with said fragile part entirely therearound.

3. The method of making a combined 105 watch-case crystal and rim, said crystal having an abrupt change in the direction of its periphery, which consists in forming a shallow sheet-metal cup with its walls following the required contour of the crystal, suitably 110 shaping said walls all around to retentively engage an appropriate part of a watch case, and suitably shaping said walls all round to retentively engage a contained fragile part, then cutting out the bottom of the cup excepting narrow stretches around adjacent to 115 said walls to form said rim, and then inserting said fragile part of appropriate contour in said rim and suitably engaging the walls of said rim with said fragile part entirely therearound.

4. The method of making a combined 120 watch case crystal and rim, said crystal having an abrupt change in the direction of its periphery, which consists in making a shallow sheet metal rim, or frame, with its walls 130

following the required contour of the crystal, and then inserting said crystal of appropriate contour in said rim, and suitably engaging the walls of said rim with said crystal.

5. The method of making a combined watch case crystal and rim, said crystal having an abrupt change in the direction of its periphery, which consists in forming a shallow sheet metal rim, or frame, with its walls 10 following the required contour of the crystal, and suitably shaping the exterior walls

of said rim or frame, so that said rim or frame can be held in an appropriate part of a watch case, and then inserting said crystal of approximate contour in said rim, and 15 suitably engaging the walls of said rim with said crystal.

ARTHUR W. WADSWORTH.
